SLOPE MEASURING SLED

William V. Kielhorn, Granada Hills, Calif., assignor to
Lockheed Aircraft Corporation, Burbank, Calif.

Filed May 1, 1964, Ser. No. 79,765

Term of patent 14 years

(Cl. D52—6)

FIG. 1

FIG. 2

FIG. 4

FIG. 3

FIGURE 1 is a perspective view of a slope measuring sled showing my new design;

FIGURE 2 is a top plan view thereof;

FIGURE 3 is a front elevational view of the sled; and
FIGURE 4 is a side elevational view of the sled.

I claim:

The ornamental design of a slope measuring sled, as shown.
